AUSTIN G. McHUGH, OF YOUNGSTOWN, OHIO.

MANDREL CHANGING AND COOLING MACHINE.

Application filed January 11, 1928. Serial No. 245,858.

A process for the manufacture of pipes and tubes has recently been developed which comprises essentially the rapid intermittent forging of the leading end of a pierced, heated, longitudinally reciprocating ingot, supported on a mandrel, by means of a pair of peculiarly grooved rolls rotating in opposite directions and in a direction opposed to the forward movement of the ingot, with the result that each time the ingot is presented to that portion of the rolls grooved to form a pass of predetermined diameter corresponding to the exterior diameter of the tube it is desired to produce, a portion of the ingot is reduced in size and brought thereto; thus the tube is progressively formed and gradually projected beyond the rolls until the whole of the metal in the ingot has passed between them. This process is commercially known as the "Pilger" process and the tube mill designed for operation in accordance therewith as a "Pilger" mill.

In carrying out the process, a cold cylindrical mandrel having an exterior diameter corresponding to the interior diameter of the pipe or tube which is to be formed is inserted in the pierced heated ingot after the latter is brought to the mill from the heating furnace and is retained in the ingot as the latter is gradually and progressively formed into the pipe or tube, after which the mandrel is stripped therefrom by suitable mechanism. During the period while the mandrel is in the ingot it becomes highly heated both from its physical contact therewith and also from the heat generated by the forging of the ingot in its progress through the rolls of the mill; in consequence, after each pipe or tube has been formed and the mandrel has been stripped therefrom, the latter has to be removed from the mill and a fresh cold mandrel supplied for insertion in the succeeding ingot.

It is therefore a principal object of the present invention to provide means for removing the heated mandrel from the mill and for supplying another cooled mandrel thereto for insertion in the next ingot.

A further object of the invention is the provision of means for effectively cooling the hot mandrel after removal from the mill so as to enable it to be used again after a proper interval, and more particularly to provide means for effecting this cooling slowly by exposing the mandrel to the air,

thereby avoiding any distortion of the mandrel in shape, diameter or length, as well as the setting up of excessive internal strains in the mandrel which frequently results from too rapid cooling; in consequence, by the use of the present invention the useful life of the mandrels is prolonged.

A still further object of the invention is to provide a machine adapted for consecutively removing the heated mandrels from the mill and comprising a suitable conveyor mechanism for receiving the mandrels so removed and adapted to move them in a predetermined path of sufficient length to enable them to be slowly and adequately cooled by exposure to the air and to then consecutively feed the cooled mandrels back to the mill, the said machine being designed to effect these several functions substantially automatically and without the employment of labor additional to that normally required to operate the feeding device of the Pilger mill with which the said machine is operatively associated.

The invention further contemplates the provision of a machine of the character aforesaid which is of rugged yet relatively simple construction and therefore not liable to get out of order or become damaged under the conditions of operation to which it must necessarily be subjected including the severe duty imposed upon it in the handling of the relatively heavy mandrels.

The invention further includes other objects and novel features of design, construction and arrangement hereinafter more particularly mentioned or which will be apparent from the accompanying drawings forming a part hereof and in which I have illustrated a machine constructed in accordance with a preferred embodiment of the invention in association with a portion of a Pilger mill of well known design.

Considered in its broader aspects my mandrel changing and cooling machine comprises a mechanism disposed at one side of the ways of the Pilger mill and embodying vertically movable arms adapted to form an inclined plane down which the mandrel can roll after it is ejected from the lifting table of the mill and from which the mandrel passes to a conveyor mechanism by means of which it is carried by step-by-step motion along a predetermined path of sufficient length to enable the mandrel to be thoroughly cooled by exposure to the air.

posure to the air before it reaches the end thereof at which point it is transferred to lifting levers arranged and operated in such a way as to raise the mandrel up another inclined plane adjacent the upper end of which the mandrel passes onto movable members along which it rolls by gravity to ultimately return to the lifting table of the mill for insertion in a fresh ingot. While for convenience I have just referred to the course of a single mandrel in its passage from the lifting table through the mandrel changing and cooling machine and back to the table, it will of course be understood that in practice a plurality of mandrels are employed and successively follow the same course, so that immediately following the discharge of a hot mandrel from the lifting table a cool mandrel will be moved into position thereon, this latter mandrel having in turn been discharge from the table some time previously, the interval between the discharge of each mandrel from the lifting table and its return thereto being thus measured by the time required for the mandrel to pass through the changing and cooling machine. Consequently, by using a suitable number of mandrels and operating the machine synchronously with the rate at which the heated ingots are brought to the mill, it is possible to discharge a hot mandrel from the mill after each ingot has been forged thereby into a pipe or tube and to bring a fresh cooled mandrel into position in the mill for insertion in the following ingot without loss of time and substantially automatically. Having in mind this brief reference to the general construction and operation of the invention more detailed reference may now be made to the particular embodiment thereof which I have chosen to illustrate in the accompanying drawings.

In the said drawings, Fig. 1 is an end elevation of the mandrel changing and cooling machine in association with certain parts of the Pilger mill proper which are shown in end elevation and also in transverse section; Fig. 2 is a plan view thereof but on a smaller scale; Fig. 3 is a fragmentary section substantially on line 3—3 in Fig. 2 but on a larger scale; Fig. 4 is a similar view but showing certain of the parts in a different position; Fig. 5 is a further fragmentary substantially similar view showing certain of the parts in still another position, and Fig. 6 is a fragmentary detail section on line 6—6 in Fig. 2 but on the same scale as the preceding three figures. The same symbols are used to designate the same parts in the several figures.

As will hereinafter appear the operation of the machine is preferably effected by two separate electric motors respectively controlled by suitable switches by means of which the motors are started, stopped and reversed as required in the proper operation of the machine. As these switches may be of any

commercial type suitable for their intended functions and as the particular circuits employed in connection therewith form no part of the invention and will frequently vary in accordance with the particular switches which may be utilized, no attempt has been made in the drawings to do more than indicate the switches diagrammatically while the wiring between the switches and the motors as well as between the latter and the power line has been entirely omitted; it will thus be understood that any suitable motors, switches and connections therebetween may be employed.

Referring now to the drawings, the Pilger mill proper comprises a pair of laterally spaced longitudinally extending horizontal ways W upon which travels the feeding and reciprocating device (not shown) by means of which the heated ingot, supported on a suitable mandrel attached to the device, is fed toward and also reciprocated with respect to the rolls; between the ways is disposed a lifting table 2 arranged to be raised and lowered by any suitable and ordinarily hydraulically actuated means. A function of this table is to support the mandrel prior to its connection to and after its detachment from the feeding means and to this end the upper face of the table may be provided with a shallow V-shaped longitudinally extending depression 3. It will be understood that the means for raising and lowering the table are capable of accurate control by the operator so the table can be brought to any desired elevation within its range of movement and retained there for as long as may be desired.

The table may be provided adjacent each end with a transversely extending slot 5 in which is disposed a lifting arm 6; these arms are respectively secured to a longitudinally extending shaft 7 rotatably journaled in the table adjacent that edge thereof which is nearest the mandrel changing and cooling machine, the shaft of course being arranged below the surface of the table so as not to interfere with the movements of the mandrels thereacross as hereinafter described. The arms 6, 6 are of such shape and size as to extend substantially across the table and, when turned in a counter-clockwise direction, to lie entirely or substantially entirely within the slots. Disposed on the shaft, preferably about midway of its ends, is a dog 8 having a nose projecting from the shaft in the opposite direction from the arms 6 and adapted to engage beneath a complementary dog 9 stationarily supported on the kicker shaft 10 of the mandrel changing and cooling machine in such position that when the lift table 2 is raised to a predetermined point the dog 8 will engage the dog 9 so that further upward movement of the table is thereafter effective to rotate shaft 7 in a clockwise direction to raise the arms 6 from their housed position within

the slots 5 with the result that a mandrel M lying on the table will be rolled off the table and toward the mandrel changing and cooling machine disposed adjacent the side of the ways of the mill and which will now be more particularly described.

This machine may be provided with a base 12 extending parallel with the ways of the mill, rigidly secured to the floor and operative 10 to support a plurality of substantially similar carrier stands 13 which are longitudinally spaced apart from each other and arranged more or less in alignment with the lift table 2; as the lift table is ordinarily somewhat 15 shorter than the mandrels the carrier stands, three of which may conveniently be employed, are preferably so spaced and arranged that the distance between the outer faces of the end stands will be somewhat greater than 20 the length of the table so that full and adequate support will be afforded to the mandrels. The rear edge or face 14 of each stand is inclined upwardly and forwardly at a relatively sharp angle, that is, in the direction 25 of the mill, from the base of the stand so as to provide an inclined plane along which the mandrels are moved when returning to the mill as hereinafter described, while the upper extremity of each stand is directed more or 30 less horizontally forwardly to terminate short of the lifting table; adjacent the end of this substantially horizontally overhanging portion each stand is formed to provide a journal 35 for the rotatable kicker shaft 10 which extends parallel to the ways.

Disposed at a suitable distance behind the carrier stands is the conveyor mechanism, the structural frame of which comprises a pair of spaced girder pedestals 16, 17 at one end 40 and a similar pair of pedestals 16', 17' at the other end, the pairs of pedestals being respectively spaced apart longitudinally for a distance greater than the length of the longest mandrel which the machine is designed to 45 accommodate; extending between these pairs of pedestals and supported and secured thereon are longitudinally extending girders 18, 19, 20 preferably in the form of I-beams which serve to tie the pedestals firmly together and also to support a plurality of 50 members 22 which I term separators and which are disposed at longitudinally spaced intervals, as well as a plurality of upper skid rails 24 preferably corresponding in number 55 to the separators and arranged in alignment therewith. The separators 22 are arranged in vertical planes and extend between the girders 18 and 19 while the upper skid rails 24 extend between the girders 19 and 20. 60 Each of the separators preferably comprises a vertically extending web suitably flanged at its extremities for attachment to the girders and having a horizontal flange along its upper edge formed to provide a depression 65 adjacent the forward end of the separator

of such configuration as to readily receive and temporarily retain a mandrel when rolled thereinto. In addition to the separators 22 to which I have just referred, I also provide two pair of separators 22' having depressions 70 25 similar to the separators 22; these pairs of separators 22', however, are respectively arranged in substantial alignment with the outer carrier stands 13 and form supports for short shafts 26 on which are journaled 75 idler sprockets 27. Corresponding sprockets 28 are mounted behind the girder 20 on a sprocket drive shaft 29 suitably journaled in brackets 30 carried by the girder 20 and a substantially similar bracket secured to the 80 pedestal 17'. Between the respective pairs of sprockets are extended conveyor chains 32 to each of which are secured a plurality of dogs 33 spaced at such intervals as to receive the mandrels between them as best shown in 85 Fig. 1. The shaft 29 is extended beyond the pedestal 17' and connected through a coupling 34 and suitable reduction gear 35 with a driving motor 36 provided with a brake 37 of any well known construction.

It will thus be apparent that the separators 22, 22' and skid rails 24 together provide a surface along which the mandrels between the dogs on the upper runs of the chains will be carried along as the chains are moved by rotation of shaft 29 and it will be observed that this shaft as well as the shafts 26 on which the sprockets 27 are mounted is so located that the upper runs of the chains are slightly below the level of the said surface so 90 that the weight of the mandrels is borne on the latter and not upon the chains; preferably the rear ends of the separator flanges and the skid rails are slightly upwardly inclined from front to rear with consequent location 95 of shaft 29 a little above the plane of shafts 26.

As the mandrels are consecutively carried around the sprocket 28 they are received upon and supported by guides 40, 40' positioned in alignment with the chains and provided with curved faces 41 along which the mandrels may travel and from which they pass to the lower skid rails 42 which extend at an angle of inclination corresponding to 100 that of the upper skid rails 24 to terminate adjacent the rear ends of the skid stands 44, 44' arranged adjacent the forward end of the conveyor mechanism. The lower skid rails 42 are supported on suitably disposed girders 110 115 45, five of these rails being preferably employed. The skid stands which may be cast as integral units are provided with flanges 46 at their upper edges which are upwardly and forwardly curved from the adjacent ends of the lower skid rails so as to check the forward movement of the mandrels and also to some extent relieve the torsional strain set up in shaft 29 by the mandrels as they pass 120 125 over the rear sprockets in their descent from 130

the upper to the lower skid rails; the forward upward curvature of the flanges 46 of the skid stands also necessitates the positive lifting of each mandrel from a lower to a higher plane before it can pass over the forward end of the flange to the forwardly and downwardly inclined delivery lip or surface 47 formed by the upper edge of a bracket 48 with which each stand is provided and which conveniently substantially aligns with the carrier arms 50, 50' hereinafter more particularly described and which are supported on the carrier arm shaft 51 suitably journaled for rotation in brackets 52 disposed on the carrier stands and preferably integral therewith.

From the foregoing description of the conveyor mechanism it will be apparent that as the mandrels are consecutively delivered, as hereinafter described, to the aligned depressions 25 in the separators 22, 22' they will remain therein until moved rearwardly along the upper edges of the separators and thereafter along the skid rails by the dogs of the conveyor chains and that as the surface on which the mandrels travel is elevated above the chains the mandrels will readily roll therealong under the influence of the dogs with resulting economization in power. As the mandrels consecutively pass over the rear sprockets 28 they are supported by the dogs until the latter reach a substantially horizontal position when the weight of the mandrels is taken by the guides 40 and 40' and the mandrels from thence pass to the lower skid rails 42 along which they roll by gravity assisted by the dogs until they reach the skid stands, the upward curvature of which effectually slows up their advance until they are positively raised over the highest points of the skid stands by the operation of the dogs and thus pass to the downwardly inclined delivery lips 47 and from thence to the carrier arms which operate to raise them to a position to pass to the lifting table of the Pilger mill as hereinafter described.

As the point at which the mandrels are delivered from the mill is considerably in advance of the forward ends of the separators 22, 22' means are provided along which the mandrels may roll in their passage to the latter, said means comprising a plurality of vertically movable arms 55 respectively hinged at their rear ends in brackets 56 carried by the girder 18, the forward ends of the arms being adapted to rest in depressions 57 formed in the carrier stands with which the arms are respectively aligned. Thus when the arms are in lowered position as in Figs. 1 and 3 a gradually inclined plane or surface is provided extending from the forward ends of the carrier to a point adjacent the girder 18 along which the mandrels are free to roll, while as the upper face of the upper flange of girder 18 is substantially

horizontally aligned with the upper surface of the separators, said flange fills up the gap between the ends of arms 55 and the separators which would otherwise exist. As the momentum acquired by the mandrel as it rolls along the inclined plane formed by arms 55 is considerable, it is desirable to provide means for checking the speed of the mandrel or even for stopping it when it reaches a point adjacent the rear ends of the arms and for this purpose the brackets 56 may be slightly extended above the plane of the upper faces of the arms so as to lie in the path of the mandrel and thus form fixed stops 58 for checking or totally arresting its movement.

Reference has hitherto been made to the carrier arms 50, 50' which are mounted on the carrier arm shaft 51 to turn therewith; these arms have two functions, namely, that of raising the cooled mandrel after it passes from the skid stands to a position to be received by the kicker arms hereinafter described and that of raising the kicker arms after the mandrel has been received upon them so as to provide an inclined plane down which the mandrel may roll in its return to the lifting table of the mill. When these arms are in lowered position as in Figs. 1 and 3 their free ends are substantially aligned with the delivery lips 47 of the skid stands so that after the mandrel is delivered thereupon by the action of the chain conveyor it can roll down the carrier arms, whose upper or forward faces then in effect form a prolongation of the lips 47, until it contacts with the forwardly and upwardly inclined edges 14 of the carrier stands. After the mandrel attains this position rotation of the carrier arm shaft 51 in a counter-clockwise direction is operative to swing the carrier arms upwardly and forwardly, thus rolling the mandrel up the inclined plane formed by the carrier stands and bringing it into contact, as it nears the upper ends thereof, with flanges or ribs 60 formed on the under sides of the several arms 55 with the result that the latter are lifted and rotated in a clockwise direction about their pivots, thus rolling the hot mandrel which is then resting thereon (Fig. 3) rearwardly over the stops 58 and into the depressions 25 in the separators where it is in a position to be picked up by the approaching conveyor dog.

The lifting of the arms 55 and resulting movement of the hot mandrel as just described take place before the cold mandrel which is being raised by the carrier arms has attained the upper extremity of the sharply inclined rear edges 14 of the carrier stands and thus prior to or substantially contemporaneously with the passage of the cold mandrel to the kicker arms 62. These kicker arms, three of which may desirably be employed, are mounted on kicker arm shaft 10 heretofore mentioned so as to turn therewith, the major portion of each kicker arm extending rear-

wardly from the shaft and a much smaller portion forwardly therefrom so as to fill in the gap which would otherwise exist between the shaft and the adjacent edge of the lifting 5 table of the mill. Normally the rearwardly extending parts of the kicker arms are supported on stops 64 mounted on the carrier stands and these stops are so located and the kicker arms so formed that the upper edges 10 of the latter will substantially align with and conform to the adjacent surfaces 14 of the carrier stands so that as the cold mandrel is rolled up the latter by the carrier arms the kicker arms will not interfere with its movement. The under surface or edge of the rear 15 end of each of the kicker arms is preferably slightly convexed to provide a cam-like surface 65 adapted to be engaged by the adjacent carrier arm when the latter approaches 20 the end of its upward or forward movement in such manner as to raise the kicker arm; to facilitate this action the free end of each carrier arm, which is preferably substantially T-shape in cross section so as to provide a relatively 25 broad face for contact with the mandrel, may be cut away at one side in alignment with the superjacent kicker arm for a suitable distance so as to provide a shoulder 30 66 adapted to cooperate with the cam surface 65 of the kicker arm so as to raise the latter from its normal position as the carrier arm approaches the end of its movement and thus swing the kicker arm to substantially the position shown in Fig. 5. As the cold mandrel 35 prior to this lifting movement of the kicker arms has reached a position above the latter, the mandrel is thus raised from the carrier stands by the operation of the kicker arms and then rolls down the inclined upper edges 40 of the latter onto the lifting table 2 of the mill which, subsequently to the ejection of the hot mandrel therefrom, has been lowered by the operator to a position to properly receive the cold mandrel as it rolls thereonto 45 from the kicker arms in the manner just described.

It will be apparent from the foregoing that in the performance of the various operations which the mandrel changing and cooling machine is intended to effect, it is necessary to oscillate the carrier arm shaft 51 so as to raise and lower the carrier arms and also to rotate shaft 29 so as to actuate the chain conveyor, this latter function being performed by the driving motor 36 as hitherto described. The requisite movement of the shaft 51 is preferably effected from the carrier arm shaft motor 70 which is provided with a suitable brake 71 and is connected through a reduction gear 72 and pinion 73 with a toothed segment 74 mounted on shaft 51; as this shaft never makes a complete revolution but only oscillates through an angle of about 90° the toothed segment 74 may be conveniently employed instead of a full gear. The requisite

starting and stopping of motors 36 and 70 and reversing of the latter may be accomplished if desired by manual operation of suitably arranged switches but for the purpose of insuring proper synchronization of the movements of the various parts of the machine, avoiding liability of injury thereto or breakage thereof through inattention of the operator and effecting its operation substantially automatically, I prefer to utilize 75 suitable switches of well known form for accomplishing certain intended functions, arranged and operating in substantially the manner now to be described.

To this end, therefore, I preferably mount 80 a switch S on the beam 18 and arrange a trip lever S', operative to control the switch, in such position that it will be depressed by the hot mandrel substantially as the latter reaches the stops 58. This switch is so connected 85 that on depression of the lever S', the carrier arm shaft motor 70 will be set in operation in a direction proper to raise the carrier arms from lowered position (Fig. 3) with the result that the cold mandrel which has theretofore been delivered to the carrier arms by the conveyor will be started in its upward movement along the carrier stands. The control circuit in which the switch S is interposed is carried through a limit switch LS 90 positioned adjacent shaft 51 and so constructed that when said shaft has rotated sufficiently to bring the carrier arms to their uppermost position, it will automatically interrupt the circuit to the motor 70; as soon as the current is thus cut off the motor, brake 71 functions to stop the latter and hold the carrier arms in raised position. A push button or switch (not shown) is arranged near the operator to enable him to reverse motor 105 70 as soon as the cool mandrel has been delivered to the lifting table of the mill so as to effect the return of the carrier arms to lower or normal position, upon the attainment of which limit switch LS again operates to cut 110 off the current from the motor which is then brought to rest by the brake. If desired, an additional extreme limit switch ELS may be arranged for actuation by suitable stops X, X' on shaft 51 upon the attainment of the 115 maximum desired movement of the shaft in either direction so that in case switch LS does not properly function for any reason the emergency limit switch will positively shut off the current to the motor and thereby prevent any damage which might occur should shaft 51 rotate through a greater angle in either direction than it is normally intended to do.

I also mount a conveyor starting switch 125 CS adjacent shaft 51 in such position it will be actuated by an arm CS' mounted on said shaft when the latter nearly reaches the completion of its return or clockwise movement and the carrier arms have consequently al- 130

most attained their normal position. This switch when so actuated is effective to start the motor 36 thereby rotating shaft 29 and moving the chain conveyors, but as it is desirable that each movement of the latter be only sufficient to remove the hot mandrel from the depressions 25 in the separators and to deliver a cool mandrel from the skid stands to the carrier arms I have also disposed a conveyor limit switch CLS in any suitable position, conveniently adjacent the girder 20, and connect it with shaft 29 by a chain and sprocket connection or other suitable means, generally designated 77, in such manner that the current will be cut off from motor 36 and the latter stopped by brake 37 after the conveyor chains have moved for the requisite distance to effect these results. It will thus be apparent that the movement of the chains is an intermittent one and occurs in predetermined timed relation with the movements of the carrier arms so that the latter are always in a position to receive the cold mandrel when it is released from the skid stands by the action of the conveyor.

While it is believed the operation of the mandrel changing and cooling machine will be readily apparent from the foregoing description, brief reference thereto may nevertheless be properly made as follows: In Fig. 1 a hot mandrel HM is just about to pass from the lifting arms of the table 2 of the Pilger mill to the inclined plane formed by the tops 35 of the carrier stands and the lifting arms 55, while a cold mandrel CM has been delivered from the skid stands to the carrier arms and is about to be raised along the inclined edges 14 of the carrier stands on its way to the lifting table. Other mandrels are also shown in said figure between the dogs of the conveyor mechanism and it will of course be apparent that of these the mandrel M' which is nearest to the mill on the upper run of the conveyor is the hottest as it has been released from the mill for the shortest time while the mandrel M'' resting at the forward end of the skid stands is the coolest, having been released from the mill for the greatest length 50 of time. Following now the movements of the hot and cold mandrels HM and CM it will be noted in Fig. 3 that the former next passes by gravity to a point at which its progress is arrested or entirely stopped by the stops 58 on bracket 56 just before or coincident with its attainment of that position this mandrel depresses starting lever S' of switch S, thus setting in motion shaft 51 in a direction to swing the carrier arms upwardly so 55 as to raise cool mandrel CM. As explained, this mandrel is effective in its passage along the carrier stands to lift the arms 55 so as to roll the hot mandrel into the depression 25 thereby releasing switch lever S' which 60 swings back into normal position. After the

cool mandrel CM passes to a point above the kicker arms 62, the carrier arms become effective to raise the kicker arms and thereby discharge the cooled mandrel onto the lifting table of the mill which has hitherto been lowered by the operator sufficiently to conveniently receive the mandrel. Meanwhile, as soon as the carrier arms have attained the limit of their upward movement, limit switch LS becomes effective to cut out motor 70, thereby arresting further upward movement of the arms. The operator now reverses motor 70 so as to return the arms to normal position and just before they reach the latter the contact arm CS' on shaft 51 actuates the conveyor switch CS, thereby setting motor 36 into operation so as to remove the hot mandrel HM from the separators and also deliver the next cooled mandrel M'' from the skid stands to the lifting arms, thus completing the cycle of operation. Of course as soon as the thrust of the carrier arms is removed from the kicker arms the latter return by gravity to normal position on stops 64 so as to be out of the way of the path of the next 65 hot mandrel as it is discharged from the mill.

While I have herein described and illustrated with considerable particularity one form of my invention which I have found satisfactory under practical conditions of operation, I do not thereby desire or intend to in any way limit myself to any specific details of design, construction and arrangement of the various parts as the same are capable of material modification in numerous particulars 95 from the precise embodiments to which I have referred, nor do I desire or intend to confine the use of the invention to the changing and cooling of mandrels employed in Pilger or like pipe and tube mills in accordance with 100 the present practice as my invention is capable of other industrial uses if desired without departing from the spirit and scope of the invention as defined by the appended 105 claims.

Having thus described my invention, I claim and desire to protect by Letters Patent of the United States:

1. A machine of the class described comprising means for receiving a mandrel, conveying means adapted to move the mandrel along a predetermined path, means adapted to transfer the mandrel from the receiving to the conveying means, and means operative to receive the mandrel after its traverse of said path and thereafter move it to a point adjacent the receiving means.

2. A machine of the class described comprising means for receiving a mandrel, means adapted to form an inclined plane along 115 which the mandrel may roll from said receiving means, conveying means adapted to move the mandrel along a predetermined path extending in spaced planes and means adapted to receive the mandrel after its trav- 120 125 130

erse of said path and operative to move the mandrel thereafter to a point adjacent said first mentioned receiving means.

3. A machine as specified in claim 2 and including means disposed adjacent said first mentioned mandrel receiving means operative to discharge the mandrel from the machine upon completion of its traverse thereof.

10 4. A machine as specified in claim 2 in which the path along which the mandrel is moved by the conveying means is disposed in vertically spaced planes and the initial movement of the mandrel under the influence 15 of the conveying means takes place in that portion of the path lying in the uppermost of said planes.

5. A machine as specified in claim 2 in which the means adapted to receive the mandrel after its traverse of said path comprise a vertically movable carrier arm.

20 6. A machine of the class described comprising means adapted to receive a mandrel, vertically movable means extending from said receiving means and adapted when in lowered position to form an inclined plane on which the mandrel may roll away from said receiving means, a conveyor adapted to pick up the mandrel after its passage along 25 said plane and move it along a predetermined path extending in vertically spaced planes to a point of discharge disposed at a lower level than the point at which the mandrel is received by the machine, a vertically 30 movable arm adapted to receive the mandrel adjacent said point of discharge and means forming an inclined plane extending substantially to the point where the mandrel was first received by the machine and cooperative with said arm when moved about its 35 axis to raise the mandrel substantially there- to.

40 7. A machine as specified in claim 6 comprising a stop adapted to check the movement of the mandrel along said vertically movable means and prior to its engagement by the conveying means.

45 8. A machine as specified in claim 6 comprising means adapted to effect the operation of the conveying means with a step-by-step motion whereby the mandrel is moved along said path intermittently.

50 9. A machine as specified in claim 6 in which the vertically movable means are arranged for engagement by a preceding mandrel as it is raised by said vertically movable arm to thereby discharge a succeeding mandrel resting on said vertically movable means to a position where it may be engaged by the conveying means.

55 10. In combination with a vertically movable table adapted to support a mandrel and comprising means adapted to discharge the mandrel therefrom, a machine adapted to receive the discharged mandrel, convey it

along a predetermined path and return it to said table, said machine comprising members forming an inclined plane along which the mandrel may roll, an endless conveyor having a plurality of dogs spaced at intervals therealong and operative to convey the mandrel from a point adjacent said members along a predetermined path lying in vertically spaced planes, and means adapted to receive the mandrel after its traverse of said path and to then return it to a point adjacent that at which it was received from said table.

70 11. In combination with a vertically movable table adapted to support a mandrel and comprising means adapted to discharge the mandrel therefrom, a machine adapted to receive the discharged mandrel, convey it along a predetermined path and return it to said table, said machine comprising vertically 80 movable members forming an inclined plane along which the mandrel may roll after its discharge from the table, means for checking the movement of the mandrel along said members, a plurality of rails disposed in vertically 85 spaced planes, an endless conveyor having a plurality of spaced dogs and operative to move the mandrel along said rails, a plurality of movable arms adapted to receive the mandrel after its traverse of the rails and 90 means forming an upwardly inclined plane on which the mandrel can move under the influence of said arms, said vertically movable members being adapted to be raised by the mandrel in its passage along said inclined plane last mentioned to thereby cause another 95 mandrel subsequently discharged from the table and resting on said members to pass over the checking means to a position to be engaged by a dog of the conveyor.

100 12. In combination with a vertically movable table adapted to support a mandrel and comprising means adapted to discharge the mandrel therefrom, a machine adapted to receive the discharged mandrel, convey it along 110 a predetermined path and return it to said table, said machine comprising vertically movable members forming an inclined plane along which the mandrel may roll after its discharge from the table, a plurality of rails 115 disposed in vertically spaced planes, an endless conveyor having a plurality of spaced dogs and operative to move the mandrel along the rails, a plurality of movable arms adapted to receive the mandrel after its traverse of the 120 rails, means forming an upwardly inclined plane on which the mandrel can move under the influence of said arms and movable kicker arms disposed adjacent the upper end of said last mentioned means adapted to be raised by 125 said movable arms to form an inclined plane down which the mandrel can roll in the direction of the table.

13. In combination with a vertically movable table adapted to support a mandrel and 130

comprising a shaft and arms mounted thereon adapted when raised to discharge the mandrel from the table, a machine adapted to receive the discharged mandrel and then convey it along a predetermined path and return it to the table, said machine comprising means for actuating said shaft when the table is raised to a predetermined position so as to effect the discharge of the mandrel therefrom, 5 vertically movable members forming an inclined plane along which the discharged mandrel can move, stop members interposed in the path of the mandrel, conveying means operative to move the mandrel away from the table 10 along a predetermined path and to then move it toward the table in a lower plane and means including vertically movable carrier arms adapted to receive the mandrel from the conveying means and to raise it to a point adjacent that at which it entered the machine, 15 the mandrel being operative while being so raised to lift the movable arms and thereby cause a succeeding mandrel resting thereon to pass over said stop members to a position 20 to be engaged by said conveying means.

14. In combination with a vertically movable table adapted to support a mandrel and comprising a shaft and arms mounted thereon adapted when raised to discharge the mandrel from the table, a machine adapted to receive the discharged mandrel and then convey it along a predetermined path and return it to the table, said machine comprising means for actuating said shaft when the table is 30 raised to a predetermined position so as to effect the discharge of the mandrel therefrom, vertically movable members forming an inclined plane along which the discharged mandrel can move, stop members interposed in the path of the mandrel, conveying means operative to move the mandrel away from the table along a predetermined path and to then move it toward the table in a lower plane, means including vertically movable carrier arms adapted to 35 receive the mandrel from the conveying means and to raise it to a point adjacent that at which it entered the machine, and kicker arms adapted to form an inclined plane along which the mandrel may roll in the direction of the table after the mandrel has been raised to a point above said arms.

15. In combination with a vertically movable table adapted to support a mandrel and comprising means operable to discharge the mandrel therefrom, a machine adapted to receive the mandrels as they are consecutively discharged from the table to convey them along a predetermined path and return them 55 to the table, said machine comprising conveying mechanism operative to move the mandrels along said path, means for transferring the mandrels to the conveying mechanism after they are discharged from the table, and means adapted to consecutively re-

ceive the mandrels from the conveying mechanism after they have traversed said path and return them to the table.

16. In combination with a vertically movable table adapted to support a mandrel and comprising means operable to discharge the mandrel therefrom, a machine adapted to receive the mandrels as they are consecutively discharged from the table, to convey them along a predetermined path and return them to the table, said machine comprising conveying mechanism operative to move the mandrels along the path, means for transferring the mandrels to the conveyor mechanism after they are discharged from the table, means including vertically movable carrier arms adapted to receive the mandrels consecutively from the conveying mechanism after they have traversed said path and to return them to the table, and means for effecting a step-by-step movement of the conveying mechanism in timed relation with the movements of the carrier arms.

17. In combination with a vertically movable table adapted to support a mandrel and comprising means operable to discharge the mandrel therefrom, a machine adapted to receive the mandrels as they are consecutively discharged from the table, to convey them along a predetermined path and return them to the table, said machine comprising an endless conveyor having a plurality of spaced dogs adapted to receive the mandrels between them, means for transferring the mandrels to the conveyor after they are discharged from the table, means including vertically movable carrier arms adapted to consecutively receive the mandrels from the conveyor and to return them to the table, and means for operating the conveyor in timed relation with the movements of the carrier arms whereby the conveyor will be moved a predetermined distance each time the carrier arms are returned to a predetermined position.

18. A machine adapted to receive heated mandrels as they are consecutively discharged from a tube mill, to convey them in a predetermined path to allow them to cool by exposure to the air, and to consecutively return the cooled mandrels to the mill, said machine comprising means for receiving the mandrels, an endless conveyor adapted to cause movement of the mandrels along said path initially in a direction away from the mill and subsequently in a direction toward the mill, means for transferring the hot mandrels to the conveyor, means for transferring the cooled mandrels from the conveyor to the mill and including elements forming an inclined plane and vertically movable carrier arms adapted to move the mandrels along said plane, and means for actuating the conveyor in timed relation with the movements of the carrier arms whereby each time said arms are

brought to lowered position the conveyor will be actuated to discharge a cooled mandrel onto said arms.

19. A machine adapted to receive heated mandrels as they are consecutively discharged from a tube mill, to convey them in a predetermined path to allow them to cool by exposure to the air and to then consecutively return them to the mill, said machine comprising an endless conveyor adapted to move the mandrels along said path, movable members adapted to form an inclined plane along which the mandrels can roll as they are discharged from the mill to a point adjacent the conveyor, means for returning the mandrels to the mill as they are consecutively discharged from the conveyor and including elements forming an inclined plane and vertically movable carrier arms operative to move the cooled mandrels therealong, means for actuating the conveyor and the movable arms in timed relation whereby each time the arms are returned to lowered position the conveyor will be advanced one step to thereby discharge a cooled mandrel onto the carrier arms, said mandrel being thereafter operative in its passage along said inclined plane under the influence of said arms to lift the movable members so as to discharge therefrom to the conveyor a hot mandrel which has just been received thereon from the mill.

20. A machine adapted to receive heated mandrels as they are consecutively discharged from a tube mill, to convey them in a predetermined path to allow them to cool by exposure to the air and to then consecutively return them to the mill, said machine comprising an endless conveyor adapted to move the mandrels along said path, means including movable members for transferring the mandrels to the conveyor, means for returning the mandrels to the mill as they are consecutively discharged from the conveyor after traversing said path and including elements forming an inclined plane, vertically movable carrier arms operative to move the cool mandrels therealong and kicker arms disposed in the paths of said carrier arms and adapted

to be raised by the latter toward the extremity of their upward movement so as to position the kicker arms to form an oppositely inclined plane down which the mandrel may roll to return to the mill, and means for actuating the conveyor and the carrier arms in timed relation whereby each time the carrier arms are returned to lowered position the conveyor will be advanced sufficiently to effect the discharge of a cool mandrel onto the carrier arms.

21. A machine adapted to receive heated mandrels as they are consecutively discharged from a tube mill, to convey them in a predetermined path to allow them to cool by exposure to the air and to then consecutively return them to the mill, said machine comprising an endless conveyor adapted to move the mandrels along said path, means including movable members for transferring the mandrels to the conveyor, means for returning the mandrels to the mill as they are consecutively discharged from the conveyor after traversing said path and including elements forming an inclined plane, vertically movable carrier arms operative to move the cool mandrels therealong and kicker arms disposed in the paths of said carrier arms and adapted to be raised by the latter toward the extremity of their upward movement so as to position the kicker arms to form an oppositely inclined plane down which the mandrel may roll to return to the mill, and means for actuating the conveyor and the carrier arms in timed relation whereby each time the carrier arms are returned to lowered position the conveyor will be advanced sufficiently to effect the discharge of a cool mandrel onto the carrier arms.

In witness whereof I have hereunto set my hand this 31st day of December, 1927.

AUSTIN G. McHUGH.
